UNITED STATES PATENT OFFICE.

JAMES HARRIS HARDY, OF CRAWFORD, MISSISSIPPI.

SPRING FROG RAIL.

1,425,253.

Specification of Letters Patent.

Patented Aug. 8, 1922.

Application filed October 10, 1921. Serial No. 506,855.

To all whom it may concern:

Be it known that I, JAMES HARRIS HARDY, a resident of Crawford, in the county of Lowndes and State of Mississippi, and a citizen of the United States, have invented certain new and useful Improvements in Spring Frog Rails, of which the following is a specification.

My invention relates to spring frog rails, the object being to present a solid rail segment between the end of the frog and the respective rail being used, this being effected automatically by the moving of the train.

In the accompanying drawings:

Fig. 1 is a top plan view;

Fig. 2 is a detail view of the rail segments and guard rails;

Fig. 3 is a plan view of the guard rails;

Fig. 4 is a transverse section on line 4—4 of Fig. 1.

The numerals 1—1' represent the main track line. The numerals 2—2' represent a side track line both sets being spaced apart longitudinally and secured to the bases 3'.

Arranged in the space is a member 3 and extending upwardly from this member are rail segments 4 and 5 which are adapted to alternatively align with the main and side track sections as hereinafter described. Ex-

tending rearwardly from member 3 are rear guard rails 6 and 7 and forwardly therefrom and integral therewith are similar guard rails 8 and 9 and guard rails 6 and 7 are preferably arranged between the rail sections 1 and 2 while the guard rails 8 and 9 are preferably outside of the rail sections 1' and 2'.

As illustrated in Fig. 1 the rail segment 5 is in alignment with the side track rail 2—2' while the rear guard rail 7 and the forward guard rail 8 bear against the rail sections 1—1'. In this position traffic is permissible upon the side rail sections 2—2' the rear guard rail 6 and forward guard rail 9 being spaced from the rails 2—2' to permit the flanges of the wheels of the train to pass.

The rail segment 5 is preferably held in this position by the following mechanism. The numeral 10 indicates a bar pivoted as at 11 to the base 3' one end thereof being connected by a link 12 pivotally connected to the rail segment 4. The numeral 13 indicates a rod pivoted as at 14 to the base 3' the inner end of this rod being pivotally connected to the outer end of the bar 10.

Received upon the rod 13 are cup members 15 and 16 and held therebetween is a compression spring 17, a nut 18 serving to adjust the compression on the spring 17. As illustrated in Fig. 1 when the rail segment 5 is properly aligned with respect to the rail section 2—2' the outer end of the bar 10 is off center and is held in that position by the compression spring 17.

When traffic is resumed upon the main line rails sections 1—1' the flanges of the wheels would strike the guard rails 7 or 8 depending upon the direction of the traffic. The forcing apart of the guard rails at one end which is in contact with the main rail at the opposite end acts as a lever in effecting a lateral movement centrally of the member 3 and causes the bar 10 to swing upon its pivot to the opposite side of the center line of the pivots 11 and 14 and causes the center segment 4 to be drawn into alignment with the rail sections 1—1' this movement serving to draw the rail segment 5 out of alignment with rail sections 2—2' this change being effected by the flanges of the first set of wheels passing through the frog, the compression spring 17 holding the mechanism in its now operative position. Stops 20 and 21 limit the movement of the guard rails. To permit this movement the rail sections 1' and 2' are undercut as at 19 and 20 to permit sufficient movement of the member 3 to effect the desired result, the undercut portion also serving to prevent an upward movement of the movable parts.

It will thus be seen that I have provided a comparatively simple and positively new mechanism for drawing into and out of alignment the different rail sections and rail segments which serve to completely close the gap or space between the main line track sections and side track sections to present a solid rail between the sections for the movement of traffic thereover. The presentation of a solid rail at this point greatly lessens the possibility of the derailing of the train.

In operation, when the train is on the rail sections 1 and 1', the flange of the first wheel of the moving train enters between the main rail and the guard rail and acts as a wedge crowding the guard rail away from the main rail which it is lying against. When the wheel flange has pro-

ceeded approximately half the length of member 3 toward the segment which closes the flange opening, the link 12 draws the bar 10 past the dead center, diverts the pressure of the spring 17, in the opposite direction and thereby throws the member 3 against the opposite set of rails. This moves the whole member 3 a greater distance than the thickness of the wheel flange, and gives a clear opening for the flange of the wheel to pass.

I claim:

1. A spring rail frog comprising a frog point, a track-rail, a side-track rail, rail segments one of which is normally in alignment with the track or side-track rail, and means connected to the respective rail segments and parallel with the track-rail and side track-rail, whereby the rail segment of the unused track is moved laterally by the moving train.
2. A rail frog comprising a frog point, a track-rail, a side track-rail, rail segments interposed between the frog rail point and the end of the track and side track-rails, guard rails extending forwardly and rearwardly of the respective rail segments, means for normally holding one of the rail segments in alignment with its respective rail section, said means adapted to be actuated by the guard rail sections when the latter are engaged by the wheels of the mov-

ing train, whereby the rail segment of the used track-rail may be moved laterally.

3. A frog rail comprising a frog point, a main track-rail, a side track-rail, rail segments interposed between the frog point and the ends of the main track and side track-rails, guard rails extending forwardly and rearwardly from the rail segments being arranged parallel with the main and side track-rails, and resilient means comprising a pivoted bar pivotally connected at one end to the rail segments and provided with spring tensioning means for alternately holding one of the rail segments in its aligned position.

4. A rail frog comprising a frog point, track-rails, side track-rails, guard rails parallel with the track and side track-rails, rail segments carried by the guard rails and interposed between the frog rail point and the ends of the track and side track-rails, means comprising a pivoted bar connected at one end of the rail segment, and resilient means normally off center for alternately holding one of the rail segments in its aligned position, said means adapted to be thrown off center in the opposite direction by the lateral movement of either end of the guard rail normally against the track rails.

In testimony whereof I hereunto affix my signature.

JAMES HARRIS HARDY.
